UNITED STATES PATENT OFFICE

2,566,834

MANUALLY OPERATED STARTING DEVICE
FOR OUTBOARD MOTORSRichard C. Heidner, Hartford, Wis., assignor to
West Bend Aluminum Co., West Bend, Wis., a
corporation of Wisconsin

Application January 26, 1950, Serial No. 140,705

7 Claims. (Cl. 123—185)

1
This invention relates to improvements in manually operated starting devices for outboard motors.

The operation of manually pulled starter ropes exerts a force which inconveniently rocks the motor about its horizontal pivotal connection to the swivel bracket. In addition to this, the starter rope interferes with removal of the engine hood or cover. One way of eliminating these difficulties consists of placing the starting device between the engine and swivel bracket. This is not satisfactory, however, because (a) it raises the engine which being heavier than the starting device increases the height of the combined center of gravity and (b) it is difficult to repair or replace starter springs, ropes, and pawls.

It is an object of this invention, therefore, to provide a starting device which: does not rock the outboard motor about the horizontal pivot of the swivel bracket when force is applied thereto; and is enclosed within an engine cover removable from the outboard motor without interference to such starting device, such advantages being attained without increasing the vertical height of the center of gravity of the entire outboard motor.

This object is obtained by leading the pull rope of the rewind starter mounted as customary on the top of the engine through directional devices downwardly of the engine and outwardly through an opening in a cover support carried by the outboard motor at the bottom of the engine. While such opening is above the horizontal pivot of the swivel bracket there is so little distance between such pivot and such opening that the moment about such pivot created by the force necessary to operate the starter is not large enough to overcome the opposite moment about such pivot created by the weight of the outboard motor and thus it will not rock such motor. As the pull cord passes through the cover support the cover may be removed without disturbing the starter or pull cord.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawings, in which:

Fig. 1 is a view in side elevation of an outboard motor having a starting device embodying the present invention, with part broken away and shown in section for the sake of clarity in illustration; and

2
Fig. 2 is an enlarged top plan view of the outboard motor and starting device shown in Fig. 1 with part broken away and shown in section for the sake of clarity in illustration.

Referring to the drawings by reference numerals, the outboard motor designated generally 10 has a lower leg 12 which is turnably mounted in a swivel bracket 14. The bracket 14 is adapted to be secured to the transom of the board in the customary manner and has a horizontal pivot 16 about which the outboard motor swings when it is desired to raise the lower leg 12 and propeller out of the water. The lower leg 12 carries at its upper end an engine (not shown) and a supporting plate 18. The supporting plate 18 is positioned at the bottom of the engine and has a peripheral margin which extends laterally about the engine to detachably carry a cover or hood 20 for enclosing the engine and the starting device 22.

The starting device 22 is of the rewind type, such as described in United States Patents Nos. 2,374,685 and 2,348,547. It is carried in a starter support 24 secured to the engine and is positioned above the engine so as to be engageable with the crankshaft during the starting operation. The starting device 22 has a vertical axis drum 26 on which a pull rope 28 or other flexible line or wire is wound, the pull rope leading laterally out of the starting device 22 in a substantially horizontal plane. At the place where the pull rope 28 leaves the starter support 24, a pulley 30 is rotatably mounted in a bracket 32 carried on such supporting plate. The pull rope leads over this pulley and its direction is changed approximately ninety degrees downwardly so that it leads vertically downwardly from such pulley toward the bottom of the engine. A second pulley 34 is rotatably mounted below the pulley 32 by a bracket 36 secured to the support plate 18. The pull rope leads over this second pulley and its direction is changed approximately ninety degrees upwardly so that it leads laterally in a substantially horizontal plane from said second pulley. The plate 18 is provided with a pull rope outlet or opening 38 through which the pull rope 28 extends as it leads from said second pulley. It is preferable that the outer end of the rope be provided with a handle 40.

In order to operate the starting device the handle 40 is grasped and the pull rope 28 drawn in a substantially horizontal plane outwardly of the outboard motor. This, in the manner well known to those skilled in this art, causes the crankshaft of the engine to be rotated. When the pull rope 28 is released the starting device will automatically rewind such rope on the drum 26. It is a feature of this invention that the

cover 20 may be removed from the support plate 18 without interfering with the starting device 22 or the pull rope 28 and its direction changers. Another feature of this invention is that the moment tending to rock or swing the outward motor 10 inwardly about the horizontal pivot 16 is greatly lessened by providing the pull rope with a final low substantially horizontal lead. This moment, being proportioned to the relatively short distance between such lower horizontal lead and such pivot, is not sufficient to overcome the moment of opposite direction created by the weight of the outboard motor acting vertically downwardly at a much greater distance to the right of such pivot. By using a direction changer for the pull rope, the starting device, which is much lighter than the engine, may be carried above the engine and the engine mounted closer to the horizontal plane of pivot 16. This keeps the overall center of gravity of the outboard motor lower than would be the case if the engine were raised to permit the starting device to be positioned between the engine and the horizontal plane of such pivot.

Although only one embodiment of the invention is shown and described herein, it will be understood that this application is intended to cover such changes or modifications as come within the spirit of the invention or scope of the following claims.

I claim:

1. In an outboard motor having a mounting bracket to which said motor is pivoted by a horizontal pivot, a starting device at the upper end of said motor, a pull rope extending from said device, and a direction changer having a rope-engaging portion for directing said rope first downwardly of said device and a second rope-engaging portion for directing said rope outwardly of said motor, said second portion being positioned closely adjacent said pivot whereby the moment of force tending to rock said outboard motor about said pivot when said rope is pulled to operate said starting device is reduced to an amount ineffective to rock said motor.

2. In an outboard motor, an engine at the upper end thereof having a rewind starting device mounted thereabove, a pull rope for said device extending laterally thereof, a support plate secured to said outboard motor and positioned below said starting device, an opening leading laterally through said support plate, a direction changer having a rope-engaging portion for guiding said pull rope downwardly from said starting device and a second rope-engaging portion for directing said rope laterally out through said opening, and a cover detachably carried on said support plate enclosing said engine, starting device and direction changer.

3. In an outboard motor, an engine at the upper end thereof, a support member positioned at the lower end of said engine and having a portion extending beyond the outer confines of said engine adapted to carry thereon an engine cover, a rewind starting device positioned above said engine, a pull rope for said device leading tangentially therefrom, a pulley mounted on said starting device and engageable with said pull rope to change the tangential direction thereof to a longitudinal direction with respect to said device, a second pulley mounted on said support member below said first mentioned pulley and adapted to change the longitudinal direction of said pull rope back to a tangential direction relative to said device, an opening in said support plate leading

to the exterior thereof, said pull rope extending from said second pulley outwardly through said opening and having a handle attached to the outer end thereof, and a cover for said engine and device resting on said portion above said opening whereby said cover may be removed from said outboard motor without disturbing said pull rope.

4. In an outboard motor, an engine at the upper end thereof having a rewind starting device mounted thereabove, a mounting bracket for said outboard motor having a horizontal pivot about which said outboard motor swings, a support plate secured to said outboard motor and closely positioned above said horizontal pivot, a pull rope for said device extending laterally thereof, a pulley secured to said device and engaging with said pull rope to change the direction thereof downwardly of said device, a second pulley secured to said support plate close to said horizontal pivot and changing the direction of said pull rope to laterally outward of said plate, an opening in said support plate through which said pull rope leads as it leaves the said second pulley, and a cover detachably mounted on said support plate and enclosing said engine starting device and pulleys.

5. In an outboard motor having a longitudinal axis, a pivot the axis of which is normal to said longitudinal axis upon which said motor is swingably supported, a starting device for said motor having a pull rope drum the axis of rotation of which is parallel to said longitudinal axis, a pull rope for said device, and a direction changer for said pull rope having a last place of engagement with said pull rope positioned between the planes of said pivot and drum normal to said longitudinal axis.

6. In an outboard motor having a longitudinal axis, a pivot the axis of which is normal to said longitudinal axis upon which said motor is swingably supported, a starting device for said motor having a pull rope drum the axis of rotation of which is parallel to said longitudinal axis, a pull rope for said device, and a direction changer for said pull rope having a last place of engagement with said pull rope positioned nearer to the plane of said pivot normal to said longitudinal axis than to the plane of said drum normal to such axis.

7. In an outboard motor swingably supported on a horizontal pivot with an engine above the horizontal plane of said pivot and a starting device mounted above said engine with a pull rope having an upper substantially horizontal lead, a direction changer having a first rope-engaging portion for directing said rope downwardly from said upper lead and a second rope-engaging portion positioned below said upper lead for providing a second substantially horizontal lead in said pull rope positioned below said upper lead, and a cover supporting plate positioned below said upper lead, said plate having an opening therein through which said second lead extends.
